UNITED STATES PATENT OFFICE.

JOHN B. LOCKER, OF ST. LOUIS, MISSOURI, ASSIGNOR OF ONE-HALF TO JOSEPH B. CRAWFORD.

SUBMARINE BOAT.

1,388,730.

Specification of Letters Patent. Patented Aug. 23, 1921.

Application filed September 22, 1917. Serial No. 192,733.

To all whom it may concern:

Be it known that I, JOHN B. LOCKER, a citizen of the United States, residing at St. Louis, in the county of Saint Louis City and State of Missouri, have invented new and useful Improvements in Submarine Boats, of which the following is a specification.

This invention relates to submarine boats, and one of the objects is to provide a certain novel arrangement of air tanks, with means for protecting the latter, and means for supplying air to the tanks and the interior of the vessel.

In the accompanying drawings:

Figure 1 is a view in side elevation.

Fig. 2 is a vertical longitudinal section.

Fig. 3 is a horizontal section showing more fully the blades for effecting the submerging operation, and controlling the depth at which the boat travels.

Fig. 4 is a vertical transverse section on the line 4—4 of Fig. 3.

The outline of the hull of the vessel may be substantially that shown in the drawings, the central portion being provided with a chamber or series of chambers for such use as may be desired, the upper central portion being provided with air chambers and additional air chambers being provided on the outer sides and extending longitudinally of the vessel, the chambers last mentioned being protected from injury by certain novel structure described below.

The sides of the vessel carry a plurality of air tanks extending longitudinally along

the main axis of the hull, the tanks being designated 50 and preferably formed in the manner shown although any suitable construction may be employed. These air tanks are protected by guard members 51 extending longitudinally with reference to tank 50 and providing an open chamber 52 between the guard or shield and the tank 50. Valves 54 admit air from the tank to the interior of the vessel. The tanks are of course supplied when the vessel is at the surface. Valves 55 are located as shown and permit the entrance of air when said valves are open for the purpose of supplying air to the tanks mentioned. The guard members 51 include upper and lower plane surfaces converging as shown and adding to the stability of the vessel. They are well adapted to resist lateral strain, and effectively protect the air tanks.

What is claimed is:

In a device of the class described, a hull including a plurality of compartments and air chambers, an additional air chamber located on each side of the hull and projecting laterally therefrom, the upper and lower walls of the additional chambers converging at their outer portions, means for admitting air to the chambers last named, and means for protecting each of the chambers last named, comprising a guard member extending longitudinally thereof, providing converging supporting surfaces.

In testimony whereof I affix my signature.

JOHN B. LOCKER.
